APPARATUS FOR BLEACHING WOOD PULP

Application filed March 6, 1926. Serial No. 92,867.

This invention relates to apparatus for bleaching pulp or the like, and this application is a continuation in part of our co-pending application Serial No. 10,811, filed 5 February 21, 1925.

An object of the invention is to produce an apparatus for bleaching pulp under pressure, without heat, and at high consistency.

Another object of the invention is to produce an apparatus for bleaching pulp wherein the pulp is thoroughly agitated and mixed during the bleaching process with a minimum expenditure of time and power.

The objects of our invention are realized 15 in an apparatus comprising a rotatable, air-tight retort or chamber for receiving the mixture of pulp and bleaching liquor, means for subjecting the mixture to pressure, and specially constructed baffles mounted within 20 the chamber to effectively and efficiently agitate the mixture during the bleaching process.

By our method of cold bleaching, under pressure, a tougher and more durable product is obtained than is possible in a process 25 of hot bleaching, which tends to weaken the fibres of the stock. Also, by practicing the bleaching process under pressure, better penetration of the stock by the liquor is obtained.

Another advantage of our method of bleaching in an air-tight container is that the escape of chlorine gas is prevented, thereby economizing in the cost of practicing the method.

The invention is shown in the accompanying drawing in which:

Fig. 1 is a side elevation of the apparatus;

Fig. 2 is a view taken along line 2—2 of 40 Fig. 1 showing the relative positions of the baffle plates in the chamber;

Fig. 3 is a view taken along line 3—3 of Fig. 2, showing the manner in which the baffle plates are mounted;

Fig. 4 shows the details of supporting and bracing the baffle plates; and

Fig. 5 is a view of Fig. 4 taken from the direction indicated by arrow 5 of Fig. 4.

Referring to the drawing, 1 indicates the 50 bleaching chamber or retort in the form of a spherical globe provided with trunnions 2, 2 at diametrically opposite points. The chamber is mounted for rotation about the axis of the trunnions by seating the trunnions in bearings at the top of pillars or

supports 3, 3. Rotation of the chamber is effected by means of gear 4 mounted upon one of the trunnions and connected through reduction gearing (not shown) to any suitable source of power. At a point equi-distant from the two trunnions, a man-hole 5 is formed in the chamber and is provided with a cover 6 which, when clamped over the man-hole, forms an air-tight and pressure-tight closure. The chamber is also provided 60 with an outlet valve 7, located at a point opposite the man-hole 5.

Each trunnion 2, is provided with a pipe 8, concentric with the axis of rotation, and communicating with the interior of the 70 chamber.

A series of baffle plates 9, 9', 10 and 10', are secured to the inner wall of chamber 1 and serve as mixing or agitating blades when the chamber is rotated. As will be 75 seen from Figs. 3, 4 and 5 these baffle plates are of V-shape, with the point of the V of adjacent plates pointing in opposite directions.

Referring to Fig. 2, baffles 10 and 10' 80 point in the direction of rotation, as indicated by arrows 11, and baffles 9 and 9' point away from the direction of rotation. The point or apex of each baffle, that is, the line of intersection of the two wings of each 85 baffle, is located along a straight line extending through the center of the chamber. Fig. 4 is a view of baffle 9' as viewed from the center of the chamber. As will be seen the plane of each wing or side of the baffle 90 passes through the center of the globe, and while this is the preferred construction, it is to be understood that it is not absolutely essential that the planes of the wings pass through the center. The sides or wings of 95 the baffles may be made of separate plates or the two may be formed from a single sheet. Referring to Fig. 5, it will be seen that the bottom edge of each wing conforms generally to the inner wall of the globe, but elongated notches 12 and 12' are formed in the lower edge of each baffle for a purpose which will appear hereinafter. A series of

channel bars 13 are secured to the trailing side of the wing of each baffle for the purpose of giving rigidity and strength to the plates. These channel bars preferably extend at right angles to the wall of the globe, their axes extending through the center of the globe. The baffles are secured to the wall 110

of the globe by a series of webbed angle-irons 14, which are secured on one side to the wall and on the other to the channel bars 13. The outer, narrow ends of the baffles are not provided with channel bars, but depend for their support upon an angle-iron only, as will be seen from Figs. 3, 4, and 5.

The operation of the apparatus is as follows: A quantity of pulp and bleaching liquor is admitted to the globe which is then sealed tightly against the escape of gases. The globe is then rotated at the desired speed for properly mixing and agitating the mixture. We may rely upon the gases formed during the process of bleaching to develop a pressure within the globe to assist in getting good penetration of the liquor into the stock, or we may create a pressure within the globe by introducing air, steam, or any other suitable fluid through pipes 8 at the desired pressure.

The rotation of the globe tends to raise the pulp on the up-turning side of the chamber and to cause it to flow back towards the lowermost point of the globe. This causes the pulp to move continuously in a rolling or tumbling flow in the same direction, which is effective in causing a thorough mixing of the stock and liquor. The baffles assist in raising the stock from the bottom of the globe, but in addition, they are so arranged as to cause alternate concentrating and spreading of the flow. Referring to Figs. 3 and 4, it will be seen that when baffle 9 is moving in the direction of arrow 11, it will carry a portion of the mixture along in front of it, and as it begins its upward travel the sides of the baffle form a pocket-like element and direct the flow towards the point of the baffle where it will pass over the upper edge in a concentrated stream. But with respect to baffle 10, the sides will act as deflectors for the stream and will cause the stock to spread out and pass over the upper edge of the baffle in a more or less evenly distributed manner. It will be noted that since adjacent baffles are reversed with respect to each other the flow of the mixture is subjected to alternate concentration and dispersion.

By using the particular type of container and the specially shaped baffles, we are able to thoroughly mix and bleach a given amount of pulp in less time and with less power than with other known types of bleaching machines.

The slots or notches 12, 12' formed in the bottom edge of the baffles are construction details to accommodate the baffles to seams and rivets or other fastening means in constructing the globe container, but these openings also serve for the purpose of allowing the excess bleaching fluids to drain from the pockets formed by the baffles when the machine is at rest.

While we have shown and described the use of a spherical chamber, it is to be understood that the advantageous features of our invention are not solely dependent upon the spherical form of chamber, but any other equivalent form may be used without losing the advantage of the special baffle arrangement.

While we have described our machine as applied to the bleaching art, it is apparent that it may be used as a mixer or agitator in other arts.

We claim:

1. In apparatus for bleaching pulp comprising a gas-tight spherical chamber, supported for rotation about a diametral axis, means for subjecting the chamber to pressure, and agitating blades secured to the inner wall of the chamber, adjacent blades being formed to present convex and concave surfaces respectively to the pulp and in co-operation with the spherical shape of the container to produce alternate spreading and concentration flow of the material under treatment, as the spherical chamber is rotated.

2. Apparatus for bleaching pulp comprising a gas-tight spherical chamber for receiving a mixture of pulp and bleaching liquor, means for creating a pressure within the chamber, means for rotating the chamber about a diametral axis, and agitating blades secured to the inner wall of the chamber, adjacent blades being formed to present convex and concave surfaces respectively to the pulp to produce alternate spreading and concentrating flow of the mixture as the chamber is rotated.

3. In apparatus of the kind described, the combination of a spherical rotary chamber, alternate convex and concave baffle plates arranged within the chamber and at substantially right-angles to the wall thereof, a plurality of channel bars secured to the trailing side of each baffle plate, and a plurality of angle-irons secured to said channel bars and to the wall of said chamber for holding the baffle plates in position.

4. Apparatus for treating pulp or the like comprising a spherical chamber, means for rotating the chamber, two series of similarly shaped baffles each composed of a pair of plates angularly disposed to each other secured to the inner wall of the chamber, one series being positioned in opposite direction to the other series with respect to the direction of rotation whereby the flow is subjected to alternate spreading and concentrating.

5. In apparatus for treating semifluid material, a spherical chamber mounted for rotation about a diametral axis, an agitating baffle secured to the inner surface of the chamber and composed of divergent plates, whereby as the chamber rotates the material

is caused to flow in a thin sheet over the inner edges of the plates.

6. In apparatus for treating semifluid material a spherical chamber mounted for rotation about a diametral axis, an agitating baffle mounted upon the inner surface of the chamber for spreading the material, a concentrating baffle mounted upon said surface in position to receive the material after

spreading, and composed of convergent plates forming a pocket for concentrating the material and pouring the material in a concentrated stream over the inner edges of the plates at their junction.

In witness whereof we attest our signatures.

FREDERICK G. SHERBONDY.
